UNITED STATES PATENT OFFICE

1,951,825

VENTILATOR PACKAGE

Robert G. Ferris, Harvard, Ill., assignor to Starline, Inc., Harvard, Ill., a corporation of Illinois.

Original application July 7, 1930, Serial No. 466,297. Divided and this application August 11, 1933, Serial No. 684,741.

6 Claims. (Cl. 206—46)

My invention relates, more particularly, to the packaging of ventilators provided for use on the roofs of barns, stables and the like, and which are relatively large bulky structures formed principally of sheet metal, the present application being a division of my pending application for U. S. Letters Patent Serial No. 466,297, filed July 7, 1930.

As structures of this general character have hitherto been provided the matter of cost of transportation thereof has been an important factor in the cost of the ventilators to the purchaser, in spite of the fact that prior structures have been provided in separable sections adapting them to be shipped in knocked-down condition which, while reducing the cost of transportation as compared with the cost were they to be shipped in set up condition, has not permitted of the condensing of the parts, in knocked-down condition, into a sufficiently compact assembly to render transportation charges a minor part of the cost to the purchaser.

My primary object is to provide for such nesting of the parts of a ventilator structure, in knocked-down crated condition for shipment, that they will occupy much less space than in the case of ventilators as hitherto provided and similarly conditioned, thereby permitting, in the case of transportation by rail, the storing in a car of many times the number of crated ventilators possible to be stored therein when constructed as has been the general practice hitherto.

Referring to the accompanying drawings:

Figure 1 is a perspective view of a ventilator showing it in knocked-down condition and crated for shipment in accordance with my invention.

Figure 2 is a section taken at the line 2 on Fig. 1 and viewed in the direction of the arrow.

Figure 3 is a broken sectional view taken at the line 3 on Fig. 2 and viewed in the direction of the arrow showing a detail of the assembly of Figs. 1 and 2.

Figure 4 is a similar view with the parts of the ventilator omitted.

Figure 5 is a view in elevation of the ventilator in set up condition for use, certain portions thereof being shown in section.

Figure 6 is an enlarged broken section taken at the line 6 on Fig. 5 and viewed in the direction of the arrow.

Figure 7 is a broken sectional elevation of the upper portion of the lower section of the base portion of the ventilator and the lower portion of the flared section of the base portion.

Figure 8 is a perspective view of a brace-plate forming a part of the ventilator structure.

Figure 9 is a similar view of another brace-plate employed.

Figures 10 and 11 are enlarged, broken, vertical sectional views taken through the upper edge of the lower section of the base-portion of the ventilator at different portions thereof; and

Figure 12, a plan view of one of the plurality of similar brackets forming parts of the ventilator.

The construction shown comprises a hollow pipe-like body portion open at its upper and lower ends and formed of superposed sections 12, 13 and 14, the lowermost section 12 which, as also the midsection 13, is of rectangular shape in cross section, being so shaped at its lower edge in accordance with common practice, that it is adapted to straddle and seat upon, the V-shaped roof of a barn, or other structure to be equipped with the ventilators, at the vent opening in the roof.

The section 14 is provided with an outwardly flaring ring-shaped portion 15 forming a storm-flange perforated at its lower edge as represented at 15^a to permit rain flowing into the space between it and the portion of the section 14 which it surrounds to drain therefrom, the flange 15 being riveted to the section 14, as indicated at 16, and its upper edge portion outwardly turned to form a rim, or flange, 17 containing openings to receive bolts hereinafter referred to.

Located above the section 14 and vertically spaced therefrom, is a roof-portion 18 in the form of a hollow cone on which, in accordance with common practice, is mounted a bracket cone 19 rigid therewith and shown as supporting a weather vane 20 and an ornament 21, the lower edge of the roof-portion 18 having a continuous outwardly extending flange 18^a of approximately the same diameter as the flange portion 17.

Surrounding the space between the body section 14 and the roof-portion 18 is a storm-band 22 to which substantially V-shaped brackets 23 disposed in a circular series about the inner side of the band 22 are rigidly secured, as by the rivets 24, these rivets extending through the apex portions of these brackets, the inner edges of the legs of which are formed, preferably by bending the metal of which the legs are made, into vertically disposed tube-portions 23^a slotted as indicated at 23^b.

The legs of the brackets 23 extend into the space between the body section 14, at the storm-flange 15, and the roof-portion 18, these

legs setting on the flange 17. The roof-portion 18, in turn, is supported at its flange 18^a on the legs of the brackets 23. Pins, in the form of bolts 26, extend through openings in the flange 18^a, the tube-portions of the legs of the brackets 23 and the openings in the flange 17 and rigidly clamp these parts together.

An annular mesh-member or screen, preferably of wire, and represented at 27 fits in the space 10 between the body section 14, at the storm-flange 15, and the roof-portion 18 for the usual purpose, and is held in place by ties 28 secured to the member 27 and looped about the bolts 26 at the slots 25 in the legs of the brackets 23.

15 Referring to the detailed construction of the body-sections 12 and 13 and the means for connecting them together, the section 12 is provided about its upper edge with a cornice 29 extending continuously thereabout and having an 20 inwardly bent flange 30 terminating in a depending extension 31, whereby the cornice presents a continuous downwardly opening channel 32 at which the cornice extends over the upper 25 edge of the body-section 12. At each of the upper corners of the body-section 12 is a bracket plate 33 (Figs. 5, 7 and 9) formed of a plate portion 34 and upwardly extending flanges 35 which extend upwardly into the channel 32.

The body-section 12 is provided with straps 30 36 one at each corner of the section 12 at the inside thereof, these straps extending at their upper ends into the channels 32 between the adjacent flanges 35 and the upper edge of the body-section 12 as shown (Fig. 7).

35 The bracket-plate 33, body-section 12, cornice 29 and straps 36 are permanently secured together by rivets 37 and 37^a the rivets 37 extending through the extension 31, flanges 35 of the brackets 33, the body-section 12 and the upper 40 edge of the cornice 29, and the rivets 37^a extending through the parts just mentioned and in addition through the upper ends of the straps 36 (Fig. 11). The metal of the upper edges of the cornice 29, body section 12, flanges 35 and extension 31 is indented as represented at 37^b (Figs. 9 and 10).

50 The body section 13 at its four corners is provided with plate-brackets 38 each formed of a plate portion 39 and depending flanges 40 which extend at their flanges 40 into an upwardly opening channel 41 extending continuously around the lower edge of the body-section 13 and preferably formed by bending up the metal at the lower edge of the body section 13 as represented 55 at 42.

The bracket 38 and the body-section 13 are rigidly secured together by rivets 43 extending through the flanges 40, the lower edge of the body section 13 and the flanges 42, and by indenting these parts as explained in connection 60 with the body section 12.

65 The body-sections 12 and 13 are connected together, in the set-up condition of the ventilator, by means of bolts 44 which pass through openings 35 and 46 in the brackets 33 and 38 at each corner of the body structure, as shown at one corner of Figs. 5 and 7, filler-blocks 38^a being 70 preferably interposed between these brackets 33 and 38 for resisting deflection of the plate portions 34 and 39 thereof and preventing the springing of the flange extension 31.

75 The straps 36 are provided for attachment, at their lower ends, to any suitable part of the roof of the building to be equipped with the ventilator, as for example by extending downwardly

through the opening in the roof and attached to girders of the building to aid in preventing displacement of the ventilator; these straps also serving as means for holding the body-section 12 against displacement in the crate in which the ventilator in knocked-down condition would be shipped, as hereinafter described.

80

The assembling of the parts of the ventilator for shipping purposes is represented in Figs. 1, 2 and 3 wherein a crate, constituting one of the forms which may be used, is shown at 47. In assembling the parts in the crate 47 the roof-portion 18 with the parts carried thereby is placed centrally on the bottom of the crate and secured thereto by screws 48 (one only of which is shown) extending through openings in the flange 18^a and into the two crosswise extending boards 49 and 50 forming the bottom of the crate. The structure formed of the two permanently united body-sections 13 and 14 is then positioned in the crate in surrounding relationship to the roof-portion 18 to rest on the bottom of the crate, in which position it is secured by bolts 51 extending through the openings 46 in the bracket-plates 39 and through openings in the boards 49 and 50, the 90 filler blocks 38^a being preferably interposed between the bracket plates 39 and the boards. The body-section 12 is then introduced into the crate to extend in encircling position about the structure formed of the body-sections 13 and 14 to rest at its lower edge on the bottom of the crate, the lower ends of the straps 36 being bent upwardly around the lower side boards 52 of the crate and secured thereto as by the nails represented at 95 53. The storm band 22 is then placed in the crate to surround the upper end of the body-section 14 with the tube-portions 23^a of the brackets 23 positioned directly beneath the flanges 17, and the band 22 and body-section 14 rigidly secured together by the bolts 26 which extend through the tube portions 23 and the flange 17, the band 22 thus being supported by this flange.

95

100 As will be noted from the foregoing, the relative proportioning of the several parts of the ventilator as shown permits them to be nested into highly compact knocked-down condition for shipping and to present a crated assembly of such dimensions that the number of such unit assemblies that may be stored in a box car of the usual dimensions, will exceed many times the 105 number of such ventilators which may be stored therein when crated, in accordance with common practices, it being noted that the height of the structure formed of the permanently connected body sections 13 and 14 is substantially the same 110 as the combined height of the body portion 12 and storm flange 22; and that the combined height of the roof portion 18 and the ornament 115 commonly provided on such structure is also substantially equal to the combined height of the body section 12 and storm flange 22.

110

120 Furthermore, as a matter of economy in packing and security against damage to the ventilator in shipping, the body section 12 at its lower edge portion is of substantially the same size as the cornice 29, measuring the latter about its peripheral portion. Thus these portions extend in substantially vertical alignment and are braced at the lower edge of the body section 12 and at the cornice against displacement of the body section 12 in the crate, by the same upright members of the crate, these members being represented at 125 54, thus avoiding the necessity of providing separate brace members for these parts.

125

130 While I have illustrated and described a par- 130

135

140

145

150

ticular construction of ventilator and shown its several parts in a particular nested arrangement for shipping, I do not wish to be understood as intending to limit it thereto as the invention may 5 be utilized with other constructions of ventilators and the parts thereof otherwise nested without departing from the spirit of my invention.

What I claim as new, and desire to secure by Letters Patent, is:

- 10 1. A ventilator package comprising a crate, a conduit section within and of substantially the height of the crate, a conduit section surrounding the first-mentioned section substantially throughout its entire length and adapted to support the same in operative position, said second- 15 mentioned conduit section being substantially in bracing contact with the side walls of the crate, a roof section within the first-mentioned conduit, and a storm band surrounding and suspended from the upper end portion of the first- 20 mentioned conduit section, said storm band being substantially in bracing contact with the side walls of the crate and in operative position being adapted to bridge the first-mentioned conduit section and roof section. 25
2. A nested barn ventilator package including hollow bottom and mid-sections, and means for securing the bottom of the mid-section to the top of the bottom section, the size of the bottom section being so coordinated to that of the mid-section that the bottom section, throughout its entire length, can lie outside the mid-section whereby the length of the nested parts is reduced to that of the mid-section. 30
3. A nested barn ventilator package including hollow bottom-, mid- and roof-sections, means for securing the bottom of the mid-section to the top of the bottom section, means for securing the bottom of the roof section to the top 35 of the mid-section with a ventilating aperture between roof and mid-section, the size of the
- bottom section being so coordinated to that of the mid-section that the bottom section, throughout its entire length can lie outside the mid-section and the size of the roof section being so coordinated to that of the mid-section that the former can lie substantially wholly within the latter whereby the length of the nested structure is reduced substantially to that of the mid-section. 80
4. A nested barn ventilator package including hollow bottom-, mid- and roof-sections, and a storm band means for securing the bottom of the mid-section to the top of the bottom section, means for securing the bottom of the roof section to the top of the mid-section with a ventilating aperture between roof and mid-section and for securing the storm band outside this aperture, the size of the bottom section being so coordinated to that of the mid-section that the bottom section throughout its entire length can lie outside the mid-section and the combined length of bottom section and storm band being approximately that of the mid-section so that the storm band, end to end with the bottom section, can also lie throughout substantially its entire length outside the mid-section and the size of the roof section being so coordinated to that of the mid-section that the former can lie substantially wholly within the latter whereby the height of the nested ventilator is reduced substantially to that of the mid-section. 85
5. The package of claim 4 including means for securing the storm band in nested position to a margin of the mid-section. 90
6. The package of claim 4 including means for securing the storm band in nested position to and below the upper margin of the mid-section. 95
